ELECTRIC HOT FORMING APPARATUS

George A. Waldie, Mount Gilead, Ohio, assignor
to H-P-M Development Corporation, Wilming-
ton, Del., a corporation of Delaware

Application November 22, 1944, Serial No. 564,649

10 Claims. (Cl. 219—3)

1

This invention relates to a method and apparatus for treating metals. Particularly, this invention relates to a method and apparatus for hot press working of metals into workpieces by either forming, drawing or forging.

In the forming of workpieces from heavy plates or bars of metal, or where the flow of the metal into the finished workpiece is considerable, it is of advantage to work the said metal while it is hot. By having the metal hot, deeper draws can be made, superior forgings are produced and heavy sections may be formed which would require several pressing operations and possibly annealing operations if the metal were worked cold.

Usually, the metal is preheated in a furnace and carried to the press where it is subsequently worked in a suitable die or dies between press platens. This involves the maintenance of a sizeable furnace and an inefficient cycle inasmuch as considerable heat may be dissipated in the transporting of the workpiece to the press.

Accordingly, it is a primary object of this invention to provide an improved method and apparatus for hot working metals.

It is another object to provide an apparatus for heating the metal in the press in which it is to be worked.

It is another object to provide electrical means for accomplishing the forging objects.

It is another object to provide an apparatus for heating a blank in a press and for thereafter shearing out and forming the center and uniformly heated portion of the said blank.

It is another object to provide a press having a blankholder adapted to work metal according to the foregoing objects.

These and other objects and advantages will become more apparent upon reference to the accompanying drawings, in which:

Figures 1, 2 and 3 are all diagrammatic views of a press adapted to work metal according to this invention;

Figure 4 is a diagrammatic view of a press having a blankholder, the press being adapted to work metal according to this invention;

Figure 5 is a view similar to Figure 4 but shows a modified heating arrangement for the metal to be worked;

Figures 6 and 7 show, diagrammatically, a heavy forming or forging operation performed according to this invention.

General arrangement

According to this invention, a press having

2

cooperating dies adapted to form a workpiece is equipped with electrode units adapted to clamp a blank along the periphery thereof. Electricity is then passed through the electrodes and blank so that the latter becomes heated to the proper working temperature.

When the blank has reached the proper temperature, it is sheared off between the electrodes so that the heated center portion lays over one of the die members. The working operation is then performed.

According to one modification, the shearing means may comprise a blankholder which, subsequent to the shearing operation, irons out the edges of the blank during the drawing operation in a manner well known in the blankholder art.

According to another modification, the heating electrodes merely abut the edges of a workpiece and, when the latter is heated, retract so as to drop it into a die cavity where it may be worked by a second die member.

Structural arrangement

25 Referring to Figures 1, 2 and 3 there is shown a portion of a press structure comprising a die 10 which has a cavity 12 therein. The edge of the die 10 comprises upstanding portions 14 which serve to define edges for the shearing off of the blank 16.

Réciprocably mounted above the die 10 is a die or punch member 18 adapted to be moved into the cavity 12 for forming the blank therein.

Also réciprocable toward the die 10 is a shear 20 which comprises the edge portions 22 adapted, in cooperation with the edges 14, to shear off the blank 16.

On either side of the die 10 are shown the clamps 24 which comprise a lower arm 26 and an upper arm 28 pivoted together at 30 and adapted at their outer ends to engage the edge of the blank 16.

Pinned to the arm 26 is a rod 32 which passes through the upper arm 28 and has pivotally secured thereto the cam 34. By rotation of the cam 34 the arms 26 and 28 may be moved relatively so as to clamp or unclamp the blank 16. A spring 36 assists in the opening of the arms 26 and 28 to release the said blank while a spring 38 serves to urge the complete electrode unit 24 about its pivot 30 so that the blank 16 is supported above the upper surface of the die 10.

Connected with the electrodes are the wires 40 and 42, the latter of which comprises a switch 44. The wires 40 and 42 lead to any suitable

source of electrical energy which may be direct current or alternating current as desired.

The electrodes 24 are preferably insulated from their supports by the insulating pads 46 and 48.

Operation

The apparatus is shown in Figure 1 with the blank 16 clamped between the electrodes 24 and the switch 44 closed so that electric current is passing through the said blank.

After the blank has been sufficiently heated, the switch 44 is opened and the shear 20 is advanced to its Figure 2 position. The advancing of the shear 20 presses the blank 16 against the edges 14 so that the edges 22 of the shear 20 will shear off the central portion of the blank. At this time the springs 38 yield to permit the blank to be moved downwardly.

After the shear 20 has cut off the blank, it may be retracted and the punch 18 advanced into the position shown in Figure 3. In this view the workpiece is completely formed and, subsequent to the retraction of the punch 18, the ejector 50 may be moved upwardly to eject the workpiece from the cavity 12.

The cam 34 is then rotated to permit the arms 26 and 28 of the electrodes 24 to open so that a new blank may be inserted and operated.

Modification of Figure 4

In Figure 4 there is illustrated a press having a die member 52 which comprises the shearing edges 54. A pair of clamps 56 support a blank above the edges 54 and also conduct current through the said blank for heating it to the proper working temperature.

A platen 58 is reciprocable toward and away from the die 52 by means of a ram 60. The platen 58 carries a second die member or punch 62 which is adapted to cooperate with the cavity 64 in the die 52 in order to form a workpiece.

Also carried by the platen 58 is the blankholder-shear 66 which has attached thereto the plungers 68 extending into the cylinders 70 of the platen 58. The rods 72 serve to support the blankholder 66 on the platen 58 when the latter is retracted.

A conduit means 74 connects the cylinder 70 with an inwardly opening check valve 76 and a two-way valve 78. The valve 78 is connected on its other side to an adjustable pressure relief valve 80. The valve 78 is normally open to permit communication between the conduit 74 and the relief valve 80. However, a limit switch 82 is provided which, when engaged by the cam 84 on the platen 58, actuates the solenoid 86 of the valve 78 to close the latter.

Operation of the modification of Figure 4

In operation the device of Figure 4 operates substantially as the device shown in Figures 1 to 3, inclusive, except for the blankholding action of the member 66. The main platen 58 moves downwardly toward the heated workpiece until contact of the member 66 with the said workpiece is imminent. At this time the switch 82 is actuated to close the valve 78, thus entrapping fluid in the cylinders 70. With the fluid trapped in the cylinders 70 further movement downward of the platen 58 drives the member 66 against the blank 88 and shears off the central portion thereof. As soon as the shearing operation is completed, the switch 82 opens and permits the valve 78 to open.

Further movement downward of the platen 58 then brings the member 66 into blankholding re-

lationship with the sheared off blank while the punch 62 advances into the cavity 64.

During the advance of the plunger 62 into the cavity 64 the blankholder plungers 68 advance into the cylinders 70 and expel fluid therefrom through the relief valve 80, the valve 80 being adjusted to provide suitable pressure in the cylinders 70.

Following the forming operation, the main platen is retracted, the workpiece is removed and a new blank is inserted between the electrode clamps 56.

Modification of Figure 5

The modification shown in Figure 5 is substantially identical with the form shown in Figure 4 except that the blank is gripped between the electrodes 90 and 92, the latter of which is reciprocated by the fluid motor 94. In operation, the fluid motor 94 is actuated to move the electrode 92 upwardly against the electrode 90 and, when the workpiece is heated to the proper temperature, the motor 94 is actuated so as to drop the blank upon the upper surface of the die member. Thus, it is not necessary to provide yielding means in association with the electrode clamps in order to provide for the proper shearing action of the shear. In this view the parts similar to those in Figure 4 bear similar numbers.

Modification of Figures 6 and 7

In Figures 6 and 7 is shown an apparatus comprising a stationary die 100 and a movable die or punch. A pair of electrodes 104 are adapted to be reciprocated laterally so as to engage the edge of a workpiece 106.

After the electrodes are engaged with the workpiece, electric current is passed therethrough until the workpiece has attained the proper temperature. Thereafter the electrodes are retracted to their Figure 7 position so that the heated workpiece falls into the cavity of the die 100. The punch 102 is then moved into pressing relationship with the die 100 and the workpiece 106 is thereby formed to the proper shape.

It will be apparent that this invention provides a means for rapidly and efficiently heating a blank to proper working temperature. This invention also provides means for trimming off the portion of the blank which is chilled by contact with the electrodes so that the entire piece being worked is at the necessary temperature.

It will be apparent that the apparatus shown is subject to many modifications without departing from the spirit of this invention. For example, the workpieces shown in the drawings might either be substantially rectangular blanks or circular as desired, the heating in either case being accomplished by properly positioning the electrodes around the periphery of the said blank.

Accordingly, it will be understood that I desire to comprehend such modifications and substitution of equivalents as may be considered to come within the scope of the appended claims.

I claim:

1. An apparatus for shaping metal sheets comprising a die having cavity, a reciprocable punch adapted to cooperate with said cavity for forming said sheet, electrically conductive clamp means adapted to clamp the marginal portion of said sheet and to support the same between said punch and die, means selectively operable for energizing said clamp means, and means separate from said punch and die for shearing off the marginal portions of said sheet prior to the shaping of the same by said punch and die.

2. An apparatus for shaping metal sheets comprising a die having a cavity and a shearing edge, a shaping member adapted to cooperate with said cavity for forming said sheet, a shearing member adapted to cooperate with said shearing edge in order to blank out said sheet, electrode means adapted to engage the marginal portion of said sheet and to conduct electric current through said sheet for heating the same, means for actuating said shearing member, and means for actuating said shaping member.

3. A press for shaping metal sheets comprising a die having a cavity, a shaping member adapted to cooperate with said cavity, first and second shearing members and a blank holder member, means for supporting said sheet between said die and said shaping member, means for passing electric current through said sheet so as to heat the same, means for actuating said shearing members for shearing off the edge of said sheet, means for advancing said blank holder to engage said sheet, and means for advancing said shaping member for forming said sheet.

4. A press for hot forming metal sheets comprising a first shaping member having a shearing edge, a second shaping member adapted to cooperate with said first shaping member, a blank holder having a shearing edge adapted to cooperate with the shearing edge of said first shaping member, means for supporting a metal sheet transversely between said shearing edges, means for passing electric current through said sheet for heating the same, means for advancing said blank holder so that said sheet is sheared off by said shearing edges, and means for simultaneously urging said blank holder against said sheared off blank and for advancing said second forming member into said blank.

5. A press comprising a stationary die member, a stationary shearing edge, a movable die member, a movable blank holder having a shearing edge adapted to cooperate with said first shearing edge, a platen mounting said movable die member, piston-cylinder means in said platen adapted to advance said blank holder-shear, electrically conductive clamps adapted to support a metal sheet between said die members, means for energizing said clamps for electrically heating said sheet, and means operable first to advance said blank holder-shear to blank out said sheet and thereafter to advance said second die member to form said sheet.

6. The combination in a press having a blankholder, a platen supporting said blankholder, a first shearing edge on said blankholder and a second shearing edge which is stationary, of means supporting a sheet of metal between said shearing edges, means for connecting said supporting means to a source of electrical energy for heating said sheet, means for advancing said platen to bring said shearing edges into cooperative relationship, means for preventing relative movement between said platen and said blankholder during the shearing action of said shearing edges, and means for thereafter permitting relative movement between said blankholder and said platen.

7. In a press for hot forming workpieces, spaced forming members and spaced shearing members, means for supporting a workpiece in the

space between said members, electrical means for heating said workpiece to working temperature while it is so supported, and motor means for moving said shearing members relatively toward each other for shearing off a portion of said workpiece and also for moving said forming members relatively toward each other for forming the sheared off portion.

8. In a press for hot forming workpieces, a first forming member and a first shearing member, a second forming member and a second shearing member spaced from said first members and defining a workpiece receiving space, means for supporting a workpiece in said space, electrical means for heating said workpiece to working temperature while it is so supported, and motor means selectively operable for moving said first and second members relatively toward each other for first shearing out a blank from said workpiece and for thereafter shaping it.

9. In a press for hot forming workpieces, first and second forming members, first and second shearing edges carried by said forming members and one being movable relative to its supporting member, means for electrically heating a workpiece supported between said members, means for moving said members relatively to bring said shearing edges into operative engagement, means for making said one edge rigid relative to its supporting forming member during the shearing operation, and means for thereafter making said last mentioned means inoperative to permit said one edge to move relative to its supporting forming member during the forming operation.

10. A press having a stationary die member, a stationary shearing edge, a movable die member, a movable blankholder having a shearing edge adapted to cooperate with said stationary shearing edge, a platen mounting said movable die member, piston-cylinder means associated with said blankholder and said platen responsive to relative movement therebetween to generate blankholding pressure on the former, means for supporting a workpiece between the dies and means for electrically heating a workpiece so supported, means for advancing said platen to bring said shearing edges into cooperative engagement, means for entrapping fluid in said piston-cylinder means during the shearing operation to prevent relative movement of said platen and blankholder, and means operable thereafter for making said entrapping means ineffective to permit relative movement between said platen and blankholder during the forming operation.
